UNITED STATES PATENT OFFICE.

ROBERT D. HAWKINS, OF WILMINGTON, NORTH CAROLINA.

END STRUCTURE FOR RAILWAY CARS.

Application filed November 26, 1923. Serial No. 676,974.

Metallic ends for railway cars have been devised and are now in extensive use which are made of a plurality of metallic plates having parallel corrugations formed therein 5 extending alternately inwardly and outwardly from the neutral axis of the corrugated panel. The corrugated plate is of ample strength to resist the shocks of the shifting lading and to resist the torsional 10 strains set up by the weaving of the car.

It is necessary, however, to line these metallic ends with a wooden lining so that the car may be used to transport any kind of lading. The lining prevents the moisture, due to condensation on the inside of 15 the metal plate, coming in contact with the grain lading and causing mildew, or if the car is loaded with cement, this moisture would cause hardening of portions of the 20 cement requiring resacking. There are also limitations regarding the loading of explosives prescribed by the Bureau of Explosives of the Interstate Commerce Commission. It is frequently found necessary to drive nails 25 into the side or end of the car when blocking the lading.

Corrugated ends have been lined by positioning nailing strips within the corrugated portion and nailing the lining to such nail- 30 ing strips. These nailing strips, of course, are subject to shrinkage which may cause a loose lining.

One of the objects of my invention is to 35 eliminate such nailing strips and secure the lining boards directly to the corrugated end in such a manner that each lining board bears directly against the inwardly projecting apices of the corrugations. Any thrust or load imposed upon the lining board is, 40 therefore, transmitted directly to the corrugated end and acts as a beam for only the short span of the distance between the apices and the inwardly projecting corrugations. The construction, therefore, materially 45 strengthens the lining boards, thus reducing the possibility of their breaking or splitting.

Another object of the invention is to provide means to hold the boards directly in contact with the apices of the inwardly projecting corrugations. 50

Another object of the invention is to strengthen the corrugated end by using the lining to distribute the load over several of the corrugations which is accomplished by 55 positioning the boards vertically if the cor-

rugations are positioned horizontally or vice versa, or so that the direction of the corrugation is substantially ninety degrees from the direction of the lining boards.

Another object of the invention is to have 60 the bolts so positioned that the nuts thereon are protected.

My invention may be used on box, gondola, stock or other types of railway equipment. 65

In the drawings:

Fig. 1 is a front elevation of a railway car with my invention applied thereon.

Fig. 2 is a cross section on line 2—2 of 70 Fig. 1.

Fig. 3 is a fragmentary enlarged view of my invention.

Numeral 1 represents the center sill; 2 the flooring; 3 the end sill angle; 4 the striking casting; 5 the side and end sill construction; 75 6 the corner post; all of the usual freight car; 9, 10 and 11 are metallic plates with corrugations 12 formed therein in the usual manner. The metallic plate has a corrugation formed therein having an outwardly 80 projecting curved surface. The lining boards 17 extend in a direction substantially ninety degrees from the direction of the corrugations, so that they bear directly against the metallic plate on both sides of the corrugation. 85

The bolts 18 pass through the lining and the outwardly projecting apices of the corrugation and by means of nuts 19 and washers 20 hold the boards 17 in contact therewith. The washer 20 is formed to fit the convex surfaces of the corrugated plate so that it can adjust itself to the irregularities and inaccuracies of construction and yet maintain an even bearing on the corrugated plate and also provide an even bearing for the nut 19. The concave washer also provides a weatherproof construction preventing moisture from entering the car by following the bolt. The washer 20 has projections 25 which form a recess 23 upon which the nut 19 rests. These projections form an added protection against moisture following the bolt and serve also to prevent the nut from turning. 95 100 105

A metallic strip 22 extends on the inside of the lining boards so that it is not necessary to bolt every board to every corrugation unless desired. This is illustrated in Figs. 2 and 3. This metallic continuous washer 110

may be let in the lining boards so that the inner surface of the end will be flush.

I claim:

1. In a metallic panel having a corrugation formed therein with an outwardly projecting curved surface, a washer with an interior concave surface engaging said outwardly curved surface, said washer having a recessed exterior surface, and a bolt having a nut bearing upon said recessed surface.
2. In a metallic plate wall element having

an integral corrugation formed therein with an outwardly projecting curved surface, a wooden lining contacting with said wall element on both sides of the corrugation, a washer with an interior concave surface engaging said outwardly curved surface provided with a recessed exterior surface, and a bolt passing through the lining, corrugation and washer having a nut bearing upon said recessed surface.
